UNITED STATES PATENT OFFICE.

CHARLES A. WINSHIP, OF CHICAGO, ILLINOIS.

DESIGN FOR A BADGE.

No. 39,227.

Specification for Design.

Patented March 31, 1908.

Application filed January 16, 1908. Serial No. 411,184. Term of patent 7 years.

To all whom it may concern:

Be it known that I, CHARLES A. WINSHIP, a citizen of the United States, residing at Chicago, in the county of Cook and State of Illinois, have invented a new, original, and ornamental Design for Badges, of which the following is a specification, reference being had to the accompanying drawing, forming part thereof.

The figure is an elevation of a badge showing my new design.

I claim:

The ornamental design for a badge, as shown.

CHARLES A. WINSHIP.
